UNITED STATES PATENT OFFICE.

ALFRED MARTIN, OF CHICAGO, ILLINOIS, ASSIGNOR OF ONE-HALF TO WILLIAM J. SANDBERG, OF CHICAGO, ILLINOIS.

LOOSE-LEAF BINDER.

1,269,479.

Specification of Letters Patent. Patented June 11, 1918.

Application filed September 24, 1917. Serial No. 192,857.

To all whom it may concern:

Be it known that I, ALFRED MARTIN, a subject of the Emperor of Germany, residing at Chicago, in the county of Cook 5 and State of Illinois, have invented certain new and useful Improvements in Loose-Leaf Binders, of which the following is a specification.

My invention relates to loose leaf binders 10 and has for its primary object the provision of means for shifting a plurality of leaves from one position to another within the binder while maintaining the relative positions of said leaves. 15 In connection with a binder carrying a plurality of relatively short, overlapped leaves and hinged to open, my invention relates more specifically to means for dividing a set of said overlapped leaves into two portions 20 and shifting one of said portions with relation to the other a distance equal to the height of each leaf that is exposed beyond the next superposed leaf. This shift of the two portions leaves between two adjacent 25 leaves a space sufficiently long for the insertion of an extra leaf between them while allowing for exposing the same amount of margin of all leaves. The object attained in this way is the interposition in its proper 30 place, alphabetically, of an extra ledger account leaf, for example; accomplishing the insertion quickly without disturbing the alphabetic arrangement of the other leaves in the set of leaves; and exposing to view, 35 when the binder is opened, a uniform amount of title margin of each leaf.

Other objects and advantages of the invention will appear from the following description taken in conjunction with the accompanying drawings which form a part 40 of this application and illustrate the preferred embodiment of the invention.

In the drawings:

Figure 1 is a top plan view of a loose leaf binder constructed in accordance with the principles of my invention, showing the same in open position and indicating in dotted lines an adjusted position of the parts. 45

Fig. 2 is an end elevation of the device shown in Fig. 1 with parts broken away. This view shows in dotted lines the closed position of the binder.

Fig. 3 is a fragmentary plan view of a set

of leaves adapted to be used in my improved 55 binder and shown in the relative positions they occupy in the binder wherein a uniform portion of the upper margin of each leaf, bearing the name of the customer whose account is kept on that leaf, is exposed to 60 view when the binder is opened.

Fig. 4 is a similar view of an extra leaf to be inserted in its alphabetical order among the leaves of Fig. 3.

Fig. 5 shows the leaves of Fig. 3 and illustrates two of the positions assumed by one portion of the set while the operation of my improved binder is shifting them with respect to the remainder of the set to make room for the extra leaf shown in Fig. 4. 70

Fig. 6 shows the leaves of Figs. 3 and 4 in their final positions in the binder, in which position they are in alphabetical order.

Fig. 7 is a perspective view of a portion 75 of the device of Fig. 1 illustrating it in a little less than fully open position.

Fig. 8 illustrates the lower end of one of the indexed leaves used to separate the account leaves of the binder. 80

Fig. 9 is a section on line 9—9 of Fig. 8.

Fig. 10 is a fragmentary view of the open binder.

Figs. 11 and 12 illustrate a modified form of the invention and correspond to Figs. 1 85 and 2, respectively.

In many offices records are kept on sheets such as the account leaves 11 to 14 inclusive shown in Figs. 3 and 4, these leaves being segregated into sets by their initials and being relatively short from top to bottom with respect to the binder in which they are kept; they are also overlapped as seen in Figs. 3 and 6 to expose only that uniform portion of their upper margins which bear the customer's name. These sets of leaves are ordinarily kept separate by indexed leaves inserted between them and extending substantially from top to bottom of the binder. 90 95

A front cover 15 and a rear cover 16 (see 100 Figs. 1 and 2), each including an angular portion forming one-half of the back of the binder, are joined to each other by hinges 17, 18 and 19 on a common axis. Each of these hinges comprises a male hinge-leaf 21 105 having lugs 22 and 23 at its upper and lower ends respectively in which is fixedly mounted a pintle 24, the lugs 22 and 23 being

spaced a considerable distance apart. Each hinge comprises also a female hinge-leaf 25 carrying a single lug 26 which slidably embraces the pintle 24 and is short relatively to 5 that portion of the pintle exposed between lugs 22 and 23. The leaves of each hinge have an amplitude of relative movement longitudinally of their pintle equal to the width of title margin exposed at the top of 10 each account leaf in the set shown in Fig. 3. This permits cover 15 to be moved toward the bottom of the binder—relatively to cover 16—a similar distance, as shown in dotted lines in Fig. 1.

15 Post frames 27 and 28 comprising elongated steel plates are secured respectively to the front and rear covers 15 and 16 and from these frames project arcuate leaf posts equidistant from and concentric with the 20 pintles 24. These leaf posts are all identical, but for the sake of description they are given the following numbers: The lower three on frame 27 are numbered from top to bottom respectively 29, 31 and 32; and 25 the lower three on frame 28 are numbered 33, 34 and 35. As best seen in Fig. 2, these posts extend across the closed binder from cover to cover their free ends entering recesses formed to receive them, as indicated 30 at 36 and 37 and 38 and 39 in Fig. 1.

The thick pieces 41 and 42 which together form the back of the binder are partially embraced near the bottom of the binder by flanges 43 and 44 formed respectively on 35 the hinge leaves 21 and 25 of hinge 19. Flange 43 carries an apertured arm 45 which, in the closed position of the binder, overlaps the flange 44. The piece 42 is partly cut away as at 46 beneath flange 44 40 to accommodate a flat spring 47 carrying a stud 48 which projects beyond flange 44 into the path of arm 45 and, in the closed position of the binder, engages the aperture in that arm. In this way the covers 15 and 45 16 are held against separation by rotation relatively about the pintles 24, and are also held against relative movement longitudinally of their common hinge axis. By pressing the free end of spring 47 into recess 50 46 the stud 48 is withdrawn from arm 45 and the operator may open the binder and shift its covers.

In the operation of the binder the leaves 55 11, 13 and 14 are placed on the upper posts on frame 28 with the upper, name-bearing margin of each exposed by lowering each successively superposed leaf a given distance from the one below it. The leaves are each provided with six post apertures and the 60 posts are separated from each other on the frame a distance equal to three times the given marginal width at the tops of the leaves. By this arrangement each leaf will be held in place by at least two posts and 65 cannot swing about in the binder. The

posts are offset in one frame from those in the other so that they cannot strike each other. The leaves 11, 13 and 14 being overlapped as shown in Fig. 3, the bookkeeper finds it necessary to place under the customers' accounts in the "R" set of leaves the leaf 12 of a new customer and to place that new leaf in alphabetical order in the set. The new leaf belongs between leaves 11 and 13. In binders now in use something more 70 than twenty leaves are used in a single set between the top and bottom of the binder. Considerable time is lost and confusion now results from the attempt of the bookkeeper to shift down one margin space all of the 80 leaves below 11, for instance, in order to allow the upper margin of 12 to show above that of 13 after 12 has been inserted. In the use of my invention the set shown as an example in Fig. 3 is split by the hand between leaves 11 and 13, all of the leaves from 11 up remaining on the rear cover posts and, the binder being opened, the leaves from 13 down being carried over to the left on the front cover posts. The front 85 cover is now moved, or shifted, toward the bottom of the binder, thereby lowering all those leaves of the set which it carries one marginal space with relation to leaf 11 remaining on the rear cover. This relative 90 position of the leaves is illustrated in Fig. 5, the position which leaf 13 occupied when the binder was first opened being shown in dotted lines. The bookkeeper now places new leaf 12 in the place originally occupied 100 by 13 and closes the binder with the front cover offset one marginal space with respect to the rear cover. This closing re-unites the set as seen in Fig. 6, the leaves being all 105 in proper spaced relation and in alphabetical order. But this closing also leaves the front cover and all sets of leaves above the "R" set lowered one marginal space from the remainder of the binder. Hence the operator re-opens the binder keeping the 110 whole "R" set on the rear cover posts and putting all leaves above it on the front posts; following this he slides the front cover upward on pintles 24 till the covers are in normal alinement, when he again 115 closes the binder. In this position of the covers the free ends of posts 32 and 35 engage respectively the recesses 38 and 37, while in the offset position of the covers these posts occupy respectively the recesses 120 39 and 36.

As will be readily seen from Fig. 6 the overlapped relation of the leaves makes the upper and lower ends of the set very thin, and when this occurs throughout twenty-six 125 or more sets in a binder the writing of entries near the top or bottom of the binder is interfered with. To offset this I employ between the sets of leaves in my binder indexed separating leaves of substantially the 130

- size of the covers and having thickened ends, as shown in Fig. 9. The thickness may be added to an ordinary sheet 49 by successively applied laminae 51, 52, 53 and 54.
- 5 At its outer edge each separating sheet carries the ordinary form of alphabet index, such as that marked "V" in Fig. 8.
- When one alphabetical division or set of leaves grows so large that its leaves if kept 10 together would be longer than the covers of the binder, a supplementary set may be started and kept separate from the first set, though next to it, by a separating leaf 55 provided with an index tab 56 noticeably 15 different from that of leaf 49; for instance, round instead of square as is indicated in Fig. 10. The round and square index tabs may be placed the one higher than the other in the binder so that both tabs show when 20 the book is opened to a given letter or set.
- In the modification shown in Figs. 11 and 12 the covers 15 and 16 are joined by the ordinary type of hinges and hence not shiftable longitudinally of their pivotal axis. Instead, the front cover post frame 57 is 25 slidably mounted on the front cover 15 and carries, hinged to it, a stiff sub-cover 58 which, moving with the shifted account leaves, prevents rubbing them on the front cover 15.
- 30 The frame 57 is reduced at places to form shoulders 59, the reduced portions sliding in keepers 61 which permit movement of the frame in a direction parallel to the pivotal axis of the covers. At its lower end the 35 frame 57 may be provided with a finger piece 62 for convenience in shifting it. The operation of this modified form of binder is substantially the same as that previously described.
- 40 While I have illustrated and described the preferred embodiment of the invention, it will be understood that one skilled in the art may make modifications thereof without departing from the spirit of the invention. I wish, therefore, not to be restricted to the precise embodiment shown except in so far as the same is limited in the appended 45 claims.
- I claim:
- 50 1. In a binder the combination with front and rear sets of alined leaf posts, of means holding said sets in pivotal relation to each other, said sets being mounted on said means for movement longitudinally of each other,
- 55 2. In a binder the combination of parallel, elongated post frames, leaf posts mounted on the frames, and means holding said frames in pivotal relation while permitting their relative longitudinal movement.
- 60 3. In a binder the combination with hinged covers, of a set of leaf posts mounted on each cover, said sets being movable longitudinally of each other.
- 65 4. In a binder the combination of hinged front and rear covers, and a set of leaf posts on each cover, said covers being relatively movable longitudinally of their hinge axes.
5. In a binder the combination of front and rear covers hinged together, a post frame on each cover, said frames being relatively movable longitudinally of the axis of the hinge; and arcuate leaf posts on each frame equidistant from said axis and concentric therewith.
6. In a binder the combination of front and rear covers hinged together, a post frame on each cover, said frames being relatively movable longitudinally of the axis of the hinge; and arcuate leaf posts on each frame equidistant from said axis and concentric therewith, the posts on one frame being offset with respect to those on the other.
7. In a binder the combination of front and rear covers hinged together, a post frame on each cover, said frames being relatively movable longitudinally of the axis of the hinge; and arcuate leaf posts on each frame equidistant from said axis and concentric therewith, the posts on one frame being offset with respect to those on the other and each post extending substantially from cover to cover in the closed position of the binder.
8. In a binder the combination of front and rear covers hinged together, an apertured post frame on each cover, and alined leaf posts on each frame equidistant from the axis of the hinge, the free ends of the posts of one frame entering apertures of the other frame in the closed position of the binder, and said frames being relatively movable longitudinally of the axis of the hinge in the open position of the binder.
9. In a binder the combination with front and rear post frames, and a pair of elements hinged together on a common axis, each element carrying one of said frames, of arcuate leaf posts on each frame equidistant from said axis and concentric therewith, said frames being relatively movable a given distance longitudinally of said axis.
10. In a binder the combination with front and rear post frames, and a pair of elements hinged together on a common axis, each element carrying one of said frames, of arcuate leaf posts on each frame equidistant from said axis and concentric therewith, said frames being relatively movable a given distance longitudinally of said axis, and the posts on each frame being spaced apart three times said given distance.
11. In a binder the combination with front and rear post frames, and a pair of elements hinged together on a common axis, each element carrying one of said frames, of arcuate leaf posts on each frame equidistant from said axis and concentric therewith, said frames being relatively movable a given distance longitudinally of said axis,

- 4.
- and the posts on each frame being spaced apart three times said given distance and offset to prevent their standing opposite each other in any position of the frames.
5. 12. In a binder the combination with two elements forming a cover, and leaf holding means on each element, of hinges for connecting said elements, each hinge comprising a leaf having two lugs remote from each other, and a pintle rigidly gripped by said lugs; and a leaf having a single lug slidably embracing said pintle between said two lugs and of less length axially of the pintle than the distance between said two lugs. 15
13. In a binder the combination with hinged covers, of a set of leaf posts mounted on each cover, said covers being relatively movable longitudinally of their hinged axis, and a lock for holding the covers in closed position and preventing said relative movement. 20

In testimony whereof I affix my signature.
ALFRED MARTIN.
